UNITED STATES PATENT OFFICE.

WALTER THOMPSON, OF ENGLE, NEW MEXICO.

DESIGN FOR A BED-PAN.

54,149.

Specification for Design.

Patented Nov. 4, 1919.

Application filed March 31, 1917. Serial No. 159,041. Term of patent 14 years.

To all whom it may concern:

Be it known that I, WALTER THOMPSON, a citizen of the United States, residing at Engle, in the county of Sierra and State of New Mexico, have invented a new, original, and ornamental Design for Bed-Pans, of which the following is a specification, reference being had to the accompanying drawing, forming part thereof.

Figure 1 is a perspective view of a bed pan, showing my new design.

Copies of this patent may be obtained for five cents each, by addressing the "Commissioner of Patents, Washington, D. C."

Fig. 2 is a side view of the same.

Fig. 3 is a front end view of the same.

I claim:

The ornamental design for a bed pan, as shown.

In testimony whereof I affix my signature, in presence of two witnesses.

WALTER THOMPSON.
